Patented May 28, 1912.

UNITED STATES PATENT OFFICE.

HARRY A. DOUGLAS, OF CHICAGO, ILLINOIS, ASSIGNOR TO THE ADAMS & WESTLAKE COMPANY, OF CHICAGO, ILLINOIS, A CORPORATION OF ILLINOIS.

LAMP.

1,027,529.

Specification of Letters Patent.

Patented May 28, 1912.

Application filed January 14, 1910. Serial No. 538,188.

To all whom it may concern:

Be it known that I, HARRY A. DOUGLAS, a citizen of the United States, and resident of Chicago, county of Cook, and State of Illinois, have invented certain new and useful Improvements in Lamps, of which the following is a specification, and which are illustrated in the accompanying drawings, forming a part thereof.

10 The invention relates to lamps especially adapted for use on automobiles; and its object is to improve the construction of the frame or body of the lamp in order to facilitate its manufacture, the assembling of its parts, and repairing. These objects are attained in the structure hereinafter described and illustrated in the accompanying drawings, in which—

Figure 1 is a side elevation of the lamp, 20 some portions being shown in section; Fig. 2 is a horizontal section through the body of the lamp, some parts being omitted; Fig. 3 is a detail in perspective of a part of one of the outer clamping members for securing 25 the top and bottom of the lamp together and retaining the side panels; Fig. 4 is a detail in perspective of an inner frame bar co-operating with the outer member; and Fig. 5 is a detail in perspective of one corner of 30 the lamp, its openable panel partly raised.

The lamp comprises an upper or top section, generally designated by the numeral 10, a bottom section generally designated by the numeral 11, a series of posts or bars 35 uniting the top and bottom sections and forming a part of the frame of the lamp, side panels, shown as four in number, interposed between the top and bottom members and seated against these members and the frame posts and held thereto by means of clamping bars, which also serve to reinforce the frame posts or bars to more rigidly unite the top and bottom sections.

40 The top section 10 is of sheet metal and comprises a dome 12, carried by an outstanding flange 13. The bottom 11 is also of sheet metal and comprises a cup 14 for holding the oil font 15, this cup being carried by an outstanding flange 16 and having a downwardly-projecting extension 17 which may rest upon and be secured to a supporting bracket (not shown).

45 The lamp is shown as being square, and its top and bottom sections are united by a 50 series of posts or bars 22, located at the cor-

ners. These bars may be stamped out of sheet metal and have their ends turned inwardly forming flanges 23, 24 which are seated against the inner surfaces, respectively, of the top flange 13 and the bottom flange 16. The body portion of each of these bars extends across one corner of the lamp, the center portion being flat and its side portions being bent inwardly to form shoulders 22^a perpendicular to the planes of the panels and then laterally to form outstanding flanges 22^b parallel to the planes of these panels and forming seats therefor.

As shown, two of the panels 26, 27, are of glass, each being seated within a metal frame L-shaped in cross-section, the outer flange of this frame 26^a bearing against the outer face of the glass and its standing flange 26^b being perpendicular to the plane of the panels and fitting and sliding upon the shoulders 22^a and upon the outer faces of the flanges 13 and 16, forming a snug fit with the body of the lamp for the exclusion of air currents and dust. The third panel 30 is of metal and has its edges flanged, as shown at 30^a to fit against the shoulders 22^a of the bar 22 and upon the outer faces of the flanges 13 and 16. This panel may be provided with a socket lug 31 for engaging a supporting bracket (not shown). The 40 fourth panel comprises a metal frame 32 and a sliding plate 33 having its edges folded inwardly, as shown at 34, for engaging and running upon out turned flanges 35 of the frame portion. A lug 36 is attached to the sliding panel 33 for convenience in raising it, and spring fingers 37 are attached to the upper portion of the frame member 32 for engaging ribs 38 formed on the inner face of the panel 33 adjacent its bottom, and affording means for holding this panel in its raised position to permit access to the interior of the lamp. The inner portion 32^a of the frame 32 has a sliding engagement with the shoulders 22^a of the frame bars 22.

The several panels are secured in place by means of clamping bars 18 which have their ends flanged inwardly, as shown at 19, 20 to over-lap the outer faces of the flanges 13 and 16, such flanges being slotted, as shown at 21, for the reception of retaining screws 19^a and 20^a, set through suitable apertures in the top and bottom members, and engaging threaded apertures, as 25, in

the instanding flanges 24 of the frame bars 22. The marginal portions 18^a of the bars 18 are bent to fit upon the outer faces of the panel frames 26^b and the marginal portions 5 of the members 30 and 32. Screws 28 are set through suitable apertures in the bars 18 and engage threaded apertures 29 in the bars 22, drawing the coöperating members of the two sets of bars toward each other 10 and tightly clamping the panels in place. In assembling the lamp, the screws 19^a and 20^a are not turned down tightly until the screws 28 have been firmly set up.

The font 15 and the burner carried there- 15 by are of any approved form. The wick-raising spindle 39 of the lamp may project outwardly and be lodged in a recess 40 formed in the frame 32, thus permitting the free movement of the sliding panel 33 and 20 being held thereby against dislodgement from its recess.

The various parts of the lamp are held securely and rigidly together by means of the screws set through the clamping bars. 25 Should it become necessary to replace a panel, the screws are removed from one pair of clamping bars, permitting the ready removal of the damaged panel and the insertion of a new one.

30 The invention is shown in connection with a top draft lamp, but may be used in a lamp employing any type of burner or mode of ventilation.

I claim as my invention:

35 1. In a lamp, in combination, a top section, a bottom section, a set of upright bars uniting the top and bottom sections and having their ends inturned and bearing against the adjacent faces of such sections, 40 panels seated against such bars, clamping bars coöperating with the first-mentioned bars for securing the panels, and having their ends inturned and engaging the top and bottom sections and means for securing 45 the two sets of bars to the top and bottom sections.

50 2. In a lamp, in combination, a top section, a bottom section, a set of upright bars uniting the top and bottom sections and having their ends inturned and bearing against the adjacent faces of such sections, 55 panels seated against such bars, clamping bars for binding the panels to the first-mentioned bars and having their ends inturned and engaging the outer faces of the top and bottom sections, and means for securing the various bars to such sections.

60 3. In a lamp, in combination, a top section, a bottom section, a set of framing bars uniting the top and bottom sections and hav-

ing their ends inturned and bearing against the adjacent faces of such sections, panels seated against such bars, clamping bars for binding the panels to the framing bars and having their ends inturned and slotted and 65 engaging the outer faces of the top and bottom sections, and screws setting through the slots of the clamping bars and in threaded engagement with the framing bars.

4. In a lamp, in combination, a top section, a bottom section, a set of frame bars uniting the top and bottom sections and having their side portions angular in cross-section 70 forming shoulders perpendicular to the planes of the side faces of the lamp, and panel-receiving seats parallel with such side faces, panel-frames angular in cross-section 75 for inclosing the panels and engaging the shoulders of the bars, panels seated within the frames and clamping bars binding the 80 panel-frames to the frame bars.

5. In a lamp, in combination, a top section, a bottom section, a set of frame bars uniting such sections and having their marginal portions bent to form panel seats and 85 panel-engaging shoulders, a set of panels engaging such seats and having instanding flanges slidably engaging the upper shoulders and the margins of the top and bottom sections, and clamping bars binding the 90 panel sections to their seats.

6. In a lamp, in combination, a top section, a bottom section, bars arranged in pairs detachably uniting the two sections, a frame 95 clamped between the members of two pairs of such bars, and a panel slidably carried by such frame.

7. In a lamp, in combination, a top section, a bottom section, bars arranged in pairs detachably uniting the two sections, a frame 100 clamped between the members of two pairs of such bars, a panel slidably carried by such frame, and springs for restricting the movement of the panel.

8. In a lamp, in combination, a body 105 frame, panels fitting the body frame, one thereof being removable, a font seated within the body and having a wick-raising spindle projecting beyond the walls of the body, the opposite members of that part of 110 the body frame receiving the removable panel having grooved margins forming a slideway for such panel and one of such frame members having a recess for receiving the wick-raising spindle extending 115 through its said grooved margin.

HARRY A. DOUGLAS.
